HANDLE WITH CONCEALED ATTACHING SCREW

This invention relates to flexible handles adapted to be arched to a carrying position and flattened against a carrying case wall to a non carrying position.

Heretofore, such flexible handles were attached to case walls by brackets with staked-in screws and caps secured over the brackets to enclose the same. To effectively accomplish this it was required that the bracket include curved side flanges or lips and the cap be similarly constructed and that these members be attached to each other at least at their corresponding side flanges which laterally confined the reduced slotted end of the handle too much and also limited the esthetic and decorative variability and appeal of the handle.

The primary object of the invention is to provide a flexible handle with attaching means which overcomes the above-noted disadvantages.

Another object is to provide a flexible handle with attaching means in which the bracket and cap are attached only by a headed screw whose threaded shank is adapted to extend through and be secured to a carrying-case wall.

Another object is to provide a flexible handle of the character described in which a decorative insert overlay is adhesively or otherwise secured in a recess in the cap to conceal the head of the screw.

Yet another object is to provide an economical method of assembling and securing a bracket and cap by means of a headed screw and of concealing the head with a decorative member to produce an attractive attaching means for the ends of a flexible handle.

These and other objects of the invention will become more apparent as the following description proceeds in conjunction with the accompanying drawing, wherein:

FIG. 1 is a fragmentary plan view of a handle embodying the invention;

FIG. 2 is a sectional view taken on the line 2-2 of FIG. 1;

FIG. 3 is a vertical sectional view, the screw being shown in elevation, of the cap, bracket and screw in the first stage of assembly;

FIG. 4 is a view similar to FIG. 3 of the parts secured to each other with the decorative overlay shown ready for insertion to cover the screwhead; and

FIG. 5 is a view similar to FIG. 4 showing the parts secured together in their final position ready to receive an end of the handgrip and attach the same to a carrying-case cover.

Specific reference is now made to the drawings wherein similar reference characters are used for corresponding elements throughout.

Indicated at 10 is a flexible collapsible handle of the type which contains an elongated handgrip portion 12 and reduced ends 14 with longitudinal slots 16 therethrough for slidably receiving an attaching screw. The handgrip may be made of a variety of materials, preferably resilient plastic suitably textured colored or decorated, or of a sheath of plastic through which extends, longitudinally, a leaf spring 18 which is coextensive with the handgrip and includes slots in registry with slots 16 in the handgrip.

The ends of the handgrip are attached to any carrying-case wall 20 by means of hardware 22 which is the subject matter of this invention.

An inner member or bracket 24 is provided in the form of a substantially L-shaped metallic member having a longitudinal plate 26, a depending flange 28 at one end and an upturned lip 30 at its other end forming an outwardly inclined rounded beveled edge 32. Centrally, the plate 26 includes an aperture 34 and an annular downwardly indented shoulder 36 thereabout.

An outer member or cap 38 is provided which is preferably substantially rectangular, made of metal, and of a width approximating the widest dimension of the handgrip. The cap has a pair of depending longitudinal side flanges 40 and one end flange 42, the other or inner end being open. The top of the cap has a substantially rectangular downwardly recessed portion 44 having a central aperture 46 of the same diameter

as the aperture 34 in the bracket and an annular downwardly indented shoulder 48 which is adapted to nest in the shoulder 36 of the bracket 26.

A screw is provided having a head 50 with a flat top and of thickness equal to the depth of the annular indented shoulder 48 of the cap, a smooth shank portion 52 therebeneath and a threaded portion 54 of reduced diameter which forms an annular shoulder 56 at the juncture of the two shank portions.

As shown in FIG. 3, the screw is extended through the aligned holes 34 and 46 respectively of the bracket and cap and the indented shoulders 36 and 48 thereof are nested with the head 50 of the screw seated in the indented shoulder 48 and the flange 28 of the bracket adjacent the end flange 42 of the cap. By means of an appropriate tool applied around the shank of the screw and bearing on the shoulder 56, a force is applied thereagainst in the direction of the arrows shown in FIG. 4 to peen over a locking edge 58 annularly around the indented shoulder 36 of the bracket thereby securely locking all three members together. As will be noted in FIG. 4, when this occurs, the upturned edge 30 of the bracket presses against the corresponding edge 59 of the top of the cap to form a tight engagement of the members.

Finally, an overlay in the form of a substantially plat piece 60 which is substantially coextensive with the recess 44 at the top of the cap is affixed therein, as seen in FIGS. 2 and 5, to cover and conceal the screwhead 50 whose upper flat surface had been lying in substantially the same plane as that of the recess 44. The overlay piece may be made of metal, plastic or metal-clad material which matches or contrasts esthetically with the handgrip and is preferably affixed in the recess of the cap by adhesion.

To secure the handle on the case wall 20, the shanks of the screws are made to extend through the slots 16 of the handgrip and through appropriate holes in the wall there to be retained by suitable closure nuts 62. To prevent rotation of the fixtures during tightening of the nuts and thereafter, the flange 28 of the bracket includes a pintle 64 which extends beyond the end flange 42 of the cap into a suitable opening in the case wall 20 as shown in FIG. 2. When the handgrip is pulled up against action of its inherent resiliency or its spring 18, the handgrip arches up to its carrying position and the outer ends of the slots 16 abut the shanks of the screws; and when the handgrip is released, it is resiliently urged back to its noncarrying position substantially flat against the wall as seen in FIG. 2. In the flexing of the handgrip to the arched and flattened positions the bevel 32 engages the reduced portion 14 and guides it while reducing wear.

While preferred embodiments have here been shown and described, it is understood that skilled artisans may make minor variations without departing from the spirit of the invention.

I claim:

1. In a handle having an elongated resiliently flexible collapsible handgrip; a means to attach the ends thereof to a carrying-case wall comprising a cap having depending side flanges, one end flange and an upper wall, a recess in said upper wall having an aperture therethrough, an indented annular portion around said aperture, a bracket having a substantially horizontal wall also including an aperture and an annular indented portion thereabout, said cap and bracket being assembled so that the indented portion of said cap nests in the indented portion of said bracket, a headed screw having a shank extending through said apertures and a head seated in the indented portion of said cap, an annular shoulder integral with said shank of said screw locking said shank to the underside of the indented portion of said bracket, and a decorative member coextensive with said recess in said upper wall of said cap and secured therein and covering said screwhead, the shank of said screw adapted to extend through an end of the handgrip and into a suitable hole in a carrying case.

2. The combination of claim 1 wherein said shank of said screw includes a smooth portion beneath said head and a threaded portion of reduced diameter therebetween, said

locking shoulder being formed at the juncture between said smooth and threaded shank portions.

3. The combination of claim 1 wherein said decorative member is secured by adhesion to said upper wall of said cap in the recess thereof.

4. The combination of claim 1 wherein said bracket includes a depending flange adjacent said end flange of said cap and a pintle depending therefrom adapted to enter an aperture in a carrying case to prevent rotation of the handle attaching

5

means.

5. The combination of claim 4 and an upturned lip on said horizontal wall of said bracket at the end thereof opposite its depending flange pressing against the corresponding edge of said cap forming a beveled guide edge adapted to engage an end portion of the handgrip during the raising and lowering thereof.
